UNITED STATES PATENT OFFICE.

ARTHUR H. RICE, OF BUFFALO, NEW YORK.

CHART-FORM.

SPECIFICATION forming part of Letters Patent No. 623,561, dated April 25, 1899.

Application filed October 30, 1897. Serial No. 656,917. (No model.)

To all whom it may concern:

Be it known that I, ARTHUR H. RICE, a citizen of the United States, residing at Buffalo, in the county of Erie and State of New York, have invented certain new and useful Improvements in Chart-Forms, of which the following is a full, clear, and exact description.

In the construction of chart-forms which present in a graphic form the essential events and features of history it is a desideratum that the forms should be so arranged and constructed as to be capable of adaptation to the historic events relative to any political subdivision. It is, moreover, necessary that the mechanism of such a chart-form should be so simple and so logical in arrangement that the time and attention of the student will not be occupied by such mechanism rather than by the subject in hand. It is also an essential in the construction of chart-forms of this kind that the graphic representation should be so simple and natural that the extensive aid of color or configuration will be unnecessary, since such coloring or ornamentation results in the presentation of a picture rather than the facts sought to be taught. In order to accomplish these ends, I have devised a chart-form having a central character-column and parallel index date-columns on either side of said central character-column and directly contiguous thereto and means for referring every incident and character directly to said date-columns and said central character-column simultaneously, so that by a single act and in a single concept such event or character is established in point of time and in relation to and association with the characters of said central character-column. This is most essential, for unless all intervening steps or processes, mechanical or intellectual, are to the last degree eliminated the mind of the student fails to grasp and retain the concept sought to be impressed. In the construction of such chart-forms I follow the natural, as well as the most easy, method of general arrangement of making the central series of starting-points the heads of the political organizations with which they are connected, whether imperial or republican, and the dates at which they assumed power. By this arrangement I at once present to the eye

the principal political actors and the principal political dates of any political division. But as it is necessary for the accurate and careful study of history that all facts, events, and persons should be referable to exact dates I provide, directly adjacent and contiguous to this central series of starting-points on either hand, an index date-column, which enables the student to locate every fact or person with exactness in point of time, as hereinafter more fully explained.

It is further desirable that the various events and persons should be classified, and to that end I provide columns on either hand which serve to classify such events and persons, and as the events and persons naturally subdivide themselves into civil and military, it is natural that these should be classified upon the one side and upon the other of this central character-column and the contiguous index date-columns. I also provide graphic means for indicating the period and limit of ruling dynasties, families, or parties, and by a similar arrangement indicate the different and well-recognized literary periods connected with such history. My system also provides graphic means, in connection with the other features, of representing the leading characters, both literary and political, connected with the period covered by the chart.

Referring now to the drawing herewith, in which like letters refer to like parts, A represents the main central column, in which are given the names of the several political leaders, whether they be kings, emperors, presidents, or governors, as indicated at a. The horizontal lines K K represent the limits of their political leadership with reference to the date-columns hereinafter more fully described. The column B is headed in each instance by the date marking the beginning of the reign or political supremacy of the leader whose name appears in the corresponding space in the column A and are placed as indicated at b.

C and C are date index-columns in which each year is recorded and which operate as parallel scales, an interval of space being accorded to each year, which may be large or small, according to the number of events to be recorded in connection with it.

D is a column in which are to be recorded under the adjacent dates in the date-columns the important civil events of that period. D' is a similar column in which are arranged, 5 with reference to the adjacent index date-column, the several military events of the period. The column E is devoted to wars, and I indicate the beginning, length, and termination of such wars by means of brackets, 10 as shown at N, the upper horizontal portion of the bracket indicating the beginning and the lower the closing of each war period. In a similar manner and by the use of similar brackets I indicate the relationship of the 15 several rulers or political leaders in the column H, as shown at L and M. These brackets may be readily made to distinguish different relationships either by their size and position, as here indicated, or by printing them in 20 different colors.

At the left of the date index-column C, I provide for recording the names and indicating the dates of the birth and death of the several literary characters connected with the period. 25 This I do by means of an oblique line, as shown at c, the top and bottom of which are connected by means of horizontal lines with the date index-column. In this manner the name of any particular literary character is readily 30 found, and the period of his life is readily traced and directly established in relation with a character of said central character-column at the same time. In like manner and by like means at the right of the right-hand index date-column I provide for the 35 names of the political characters of note, using similar oblique lines and parallel lines connecting with the date index-columns, as shown at d.

40 To indicate the extent of a ruling dynasty, family, or party, I employ oblique lines, as shown at I, the obliqueness and direction changing with each change of the political family or dynasty or party. For the purpose 45 of indicating the different literary periods I use similar lines, as shown at J. It will therefore be seen that I have provided means for the arrangement of those facts which are substantially common to all peoples, and that my 50 chart instead of being a mere literary production and arrangement of the facts of a given country consists rather of mechanical means for the arrangement of facts common to the history of all countries.

55 It should be noted that the various literary characters may be further classified graphically by making the oblique lines adjacent to their names, say, solid lines for prose writers, broken lines for poets, and dotted lines for 60 dramatists; but these are details of construction which are merely supplemental to the general mechanism of my invention.

I am aware that it has been proposed to construct a historical chart having a central character-column, columns on either side thereof for the classification of historical facts, and,

at the outer edges of the chart, date index-columns. I do not claim such a construction as this; but my invention possesses marked advantages over such a form of chart. By 70 arranging date index-columns adjacent to the central character-column and the columns for the classification of historical facts outside such date index-columns the reference of all the facts recorded or exhibited upon the chart 75 to the date of their occurrence and of all historical facts to a political period is much facilitated, and the mechanical arrangement can be much simplified for the reason that the horizontal lines between the date index-column and the central character-column—by which direct reference is made between the fact recorded in such column and the date of its occurrence—are entirely distinct from the horizontal reference-lines between the outer 80 columns for historical events and the date index-columns, each set of reference-lines being 85 confined to its own vertical column.

Having thus described my invention, what I claim is—

1. A chart-form comprising a main character-column, an index date-column parallel with and contiguous thereto, a separate column for the record of historical facts arranged on the side of the date index-column opposite 90 to the character-column, and independent sets of lines whereby the facts recorded in the said character-column and the said historical-facts column are respectively and independently referred directly to the date index-column, 95 substantially as set forth.

2. A chart-form consisting of a central character-column, index date-columns on either side thereof and contiguous thereto, parallel columns for the record of historical facts contiguous to said date-columns and outside thereof, a set of lines whereby the facts recorded in the central character-column are referred directly to the index date-columns, and another set of lines, independent of the 100 first set, whereby the historical events recorded in the outer columns are referred directly to the date index-columns, substantially as set forth.

3. A chart comprising a date index-column, 115 a column contiguous thereto for the record of historical facts, and a means for indicating a period including certain historical facts and referring it to the said date index-column, consisting of an inclined line extending diagonally across the said record-column to indicate the duration of said period, and horizontal lines connecting the ends of said inclined line with the date index-columns, to indicate the beginning and the end of such 120 period, substantially as set forth.

4. In a chart-form, a column arranged to receive a record of historical facts, a parallel date index-column contiguous thereto, means for indicating successive periods in the historical facts recorded, consisting of inclined lines extending diagonally across said record-

column, such lines breaking or changing direction with each succeeding period, substantially as set forth.

5. A chart-form consisting of a central character-column A, parallel date index-columns C, C, contiguous thereto, parallel columns for recording civil and military events, D, D', horizontal reference-lines connecting the historical facts recorded in these columns with 10 the date index-columns, and columns, F and

G, outside the date index-columns for the recording of literary and political facts, substantially as set forth.

In testimony that I claim the invention above set forth I affix my signature in presence of two witnesses. 15
